UNITED STATES PATENT OFFICE.

FRANK C. PARSCHE, OF CHICAGO, ILLINOIS.

DESIGN FOR A CUT-GLASS VESSEL.

SPECIFICATION forming part of Design No. 35,856, dated April 8, 1902.

Application filed March 13, 1902. Serial No. 8,115. Term of patent 7 years.

To all whom it may concern:

Be it known that I, FRANK C. PARSCHE, a citizen of the United States, residing at Chicago, in the county of Cook and State of Illinois, have invented and produced a new and original Design for a Cut-Glass Vessel; and I do hereby declare the following to be a full, clear, and exact description of the same, reference being had to the accompanying drawing, forming a part thereof.

The drawing represents a bottom plan view of a cut-glass vessel embodying my design.

The leading feature of my design consists of the representation substantially as shown in the drawing.

1 in the drawing represents a cut-glass vessel embodying my design and which is convex on its exterior surface. At the center of the vessel on the exterior surface thereof appears a substantially square panel 2, contained within which is a rosette 3, having a central superimposed or raised rosette 4. At each corner of the central square panel appears a large rosette 5, within each of which

rosettes appears a small superimposed or raised ground projection or rosette 6. Between each of these large rosettes 5 appear small rosettes 7, and within each of which small rosettes 7 appear raised rosettes or ornamental projections 8. Beneath each of the large rosettes 5 and between the central panel 2, extending from and around the said rosettes 5, are cut straight depressions or marks 9, which have the appearance on the curved surface of the article of being curved and give the effect to the eye of a wreath, as if formed by cross sheaves or feathers.

Having thus fully described my design, what I claim as new, and desire to secure by Letters Patent, is—

The design for a cut-glass vessel substantially as herein shown and described.

In testimony whereof I hereunto affix my signature in presence of two witnesses.

FRANK C. PARSCHE.
